METHOD OF PREPARING WALLS OF HOUSES
FOR HEAT INSULATION

Edward F. Cusick, Chicago, Ill.

Application November 21, 1938, Serial No. 241,502

6 Claims.

(Cl. 20—~~41~~ 101)

The main object of the present invention is to provide a very simple and efficient method of effecting heat insulation of the outer walls of buildings by the use of mineral wool, or the like, in such a manner as to overcome serious objections to the use of said insulating material.

The customary method of effecting such insulation has been to cut holes through the exterior portions of the walls at the upper ends of the spaces within the walls lying between the studs and bordered by the exterior portions and the inner lath-plaster walls, and then filling said spaces with the mineral wool, or other preferably non-inflammable material, which, in some instances, is substantially baled to form somewhat compact blocks thereof of dimensions to fit the said spaces. Said blocks or bales are dropped successively into said spaces until the latter are filled.

Loose material of this nature is blown into the hollows of the wall or is otherwise introduced.

The lath-plaster walls of these hollows are extremely porous, so that humid air passes therethrough easily from the interior of the house and on through the porous mass of insulating material to the cold inner surface of the outer wall. The moisture condenses on the last-mentioned surface and in freezing weather forms an ice or hoar-frost coat thereon which grows in thickness during a prolonged cold spell.

In warm weather this ice-coat thaws and seriously affects the outer wall portions of the hollows. The said outer wall portions of buildings are variously constructed. In the case of frame, brick-veneer or stucco walls, the innermost portions are of wood sheath on the outer face with tarred paper over which clap-boards, shingles, brick veneer or stucco are applied.

This innermost wood portion is most seriously affected by the moisture which soaks into it and can evaporate only very slowly because of the sluggish circulation of air through the insulating filler on one side and due to the sealing effect of the tar paper sheathing and outer wall on the other side, the wood being thus rotted in the course of a few years.

If the moisture penetrates to the brick veneer or stucco, the effect is bad, though not as serious as with respect to wood sheathing and the portions of the studs or furring strips to which the sheathing is directly opposed and nailed. The rusting out of the nails which secure the wood sheathing in place also results from the moisture.

The foregoing results of penetration of moisture into mineral-wool filled hollows are so se-

rious that architects generally refuse to specify or even permit the use of this type of insulating material, of which mineral wool is exemplary, to fill the wall-hollows aforesaid, and this has been so detrimental to the mineral wool industry generally, including contractors who make it their sole business to effect insulation of the walls of old houses, that the industry is threatened with collapse.

The danger resulting from a steady decrease in the business of insulating the walls of buildings has been so alarming that many thousands of dollars have been expended by the manufacturers in seeking a satisfactory solution of their problem and that of the contractors aforesaid upon whom they are dependent for orders. No solution heretofore proposed has proven satisfactory or practical for various reasons.

Insulation of walls by filling the hollows of same with mineral wool or other material possessing similar characteristics, is very cheap in comparison with other insulating means, methods and materials, and to remedy the aforesaid objections at great cost will not solve the problems of the industry, nor will any means which may affect the appearance of the exterior surfaces of the walls, such as so-called breathing holes in same, be tolerated.

The dire necessity of finding a satisfactory low cost solution of the problem presented has faced the industry for years and numerous solutions thereof have been proposed and discarded.

The present invention affords the cheapest and most practical solution of said problem that has yet been proposed so far as I am informed, and is hereinafter described in connection with the accompanying drawings.

In said drawings:

Fig. 1 is a fragmentary detail vertical sectional view of the outer wall of a dwelling, such as a frame house, showing a device employed which projects into the hollow space between the outer wall or sheathing and the inner plastered wall.

Fig. 2 is a fragmentary plan sectional view taken on the line 2—2 of Fig. 1.

Fig. 3 is a more or less diagrammatic perspective view of a liquid spraying device constituting part of the means shown in Figs. 1 and 2.

Fig. 4 is a view similar to Fig. 1 showing another device projected into the hollow spaces of the wall for cleansing the walls preparatory to the use of the device shown in Figs. 1, 2 and 3.

Fig. 5 is a view in front elevation of a cleansing device constructed in accordance with the invention for first effecting cleansing of the sur-

82 2

2,263,070

face opposed to the outer wall or sheathing of the hollow space.

Fig. 6 is a fragmentary vertical sectional view of the said cleansing device, taken on the line 6—6 of Fig. 7.

Fig. 7 is a vertical sectional view of the cleansing device taken on the line 7—7 of Fig. 5.

The method of this invention is founded on the proposition that if the lath-plaster walls of the hollows to be filled with the insulating material are sealed against the passage of humid air therethrough, the problem presented is solved, provided that this can be accomplished at a sufficiently low cost. Obviously, to effect this by application of a suitable paint to the room surfaces of the walls would be very costly in most, if not all, instances, and would meet with numerous objections from the standpoint of interior decorations.

To accomplish the purpose desired therefore requires resort to a seemingly difficult expedient, and that is to treat the surfaces of the lath-plaster walls opposed to the outer sheathing, said surfaces being obviously quite inaccessible for coating with a moisture-proof substance or compound. Because of this inaccessibility and the extreme roughness and irregularity of the surfaces to be coated, a much greater volume of coating compound is required than would be necessary to coat the room faces of said surfaces. Hence, the solution of the problem includes the necessity of providing a very efficient and also very cheap moisture proofing compound and its projection upon the surfaces in a manner that will insure substantially uniform hermetic sealing of said surfaces against the passage of air through the plaster.

In the instance illustrated, the hollow space 1 shown in Figs. 1, 2 and 4, is exemplary of the hollow spaces found in the walls of frame houses wherein the studs 2 are usually spaced apart fifteen inches from center to center, and consist generally of what is known technically as "two-by-fours" to which the outer sheathing of boards 3 and clapboards 4, or the like, are secured, there being usually a sheet of tar paper disposed between the sheathing 3 and the clapboards, or the like, constituting the outer finish or trim of the walls. In the case of brick walls, the sheathing is disposed between the inner face of the masonry and the opposed edges of the furring strips corresponding generally to the studs 2, but which are ordinarily only two inches in width and space the inner plastered wall a corresponding distance from the outer masonry. In instances of stuccoed frame houses, or brick veneered buildings, the stucco or brick veneer takes the place of the clapboards or shingle trim.

In order to introduce the insulating material into the shallow spaces of the walls, it is customary to cut holes into the outer wall, as by removing a few bricks of the masonry, or removing a clapboard and sawing out a part of the sheathing at the upper end of the hollow 3 in order to give access to the hose commonly used for blowing loose material, such as mineral wool and the like, into the hollows to completely fill the latter.

After filling the hollow spaces, the aforesaid openings are closed, and as above set forth, in cold weather atmospheric moisture finds its way into these hollow spaces through the lath-plaster walls thereof and permeates the insulating material therein; this being particularly true in the case of air-conditioned dwellings and other buildings. The air circulation within the filled

hollows is exceedingly sluggish and therefore condenses on the cold surfaces and is deposited thereon as hoar-frost or ice in cold weather. This occurs mainly on the wood sheathing because the latter presents the first cold surface of contact with the humid air.

The present invention overcomes the difficulties presented, as above described, in a very simple and efficient manner and consists mainly in first rendering the lath and plaster surface of the hollows to be filled with the insulating material, substantially moisture-proof by coating the same with a suitable moisture-proofing liquid before introducing the insulating material. However, before the said moisture proofing liquid can be effectively applied to the surface last-mentioned, the latter must be freed of dust which accumulates upon the same in the course of time, especially in the case of frame houses.

The invention, therefore, contemplates a method of effecting insulation of walls by first effecting the removal of dust from surfaces to be sprayed with a moisture-proofing liquid and then applying said moisture-proofing liquid in such a manner as to reduce to a minimum the permeability of said lath-plaster walls by atmospheric air.

In order to accomplish this result efficiently, I provide a device such as is shown more or less diagrammatically in Figs. 5, 6 and 7, which comprises a hollow tubular member 5 which is equipped with perforations 6 in the portion of its wall which is to be opposed to the surface to be cleansed of accumulated dust. The said tubular member 5 preferably constitutes an integral part of the nozzle portion 7 of a vacuum apparatus which is connected with a vacuum hose 9 by means of a suitable coupling 10, the said hose 9 being connected at its other end with a suitable suction device, such as a fan or suction pump, (not shown). Integral with the member 7 is a duct 11 connected at its upper end with a hose 12, the latter being connected with a suitable source of compressed air. The duct 11 is also integral with the tubular member 5 and supplies compressed air to the latter.

The length of the tubular member 5 from end to end will be slightly less than the distance between adjacent studs 2 or corresponding furring strips and the greatest width of the device of Figs. 5 and 7 from front to rear will be such as will enable it to be caused to travel within the wall hollows aforesaid. The said device of Figs. 5—7 inclusive, is made preferably of a resilient rubber so that it may be introduced through a relatively small opening in the outer wall of the hollow space to be filled. The perforations of the member 5 are disposed angularly to the vertical plane of the surface to be cleansed to direct jets of compressed air angularly, upwardly and downwardly, respectively, the upwardly directed jets being intended to penetrate the recesses under the key formations of the plaster.

In operation, the said device of Figs. 5—7 inclusive, suspended from the lower end of the hoses 9 and 12, is dropped to the bottom of the hollow space and the means for supplying compressed air to the tubular member 5, and the fan or suction pump connected with the hose 9, are then set into operation, so that as the compressed air is projected against the lath and plaster surface to be cleansed, the dust-laden air will be sucked into and through the nozzle 7 and hose 9 and thus removed from the hollow, so that the dust may not be permitted to settle

again upon the surfaces from which it has been removed. Preferably the capacity of the suction hose 8 and the suction equipment connected therewith will be such as to remove dust-laden air more rapidly than it accumulates in said hollows.

After so cleansing said surface, the said device is withdrawn from the hollow and the nozzle 13 of a paint spraying device is dropped into the bottom of the hollow with the conventional discharge elements of the paint-spraying devices, (represented diagrammatically by the perforations 14 of the nozzle 13 opposed to the lath and plaster surface) and the spraying of liquid against the latter is then effected by gradually moving the nozzle 13 upwardly by pulling in the feed hose 15, thereby causing the entire lath and plaster surface aforesaid to be coated with a suitable moisture-proofing liquid which may consist of paint, but which is preferably composed of a coagulable liquid wax compound or the like. The nozzles of the said spraying device are disposed similarly to the perforations of the member 5 to cause the liquid to be projected into recesses in the plaster keys.

An exemplary suitable compound which is very cheap and extremely efficient comprises,

Wax emulsion	33 parts more or less by weight
Sodium silicate solution	66 parts more or less by weight
Aluminum powder	1 part more or less by weight

Various waxes, rosins, resins or gums may be used, because of their emulsibility, to form impermeable coatings on walls or surfaces subjected to water, vapor or moisture. The above materials may be used to form an emulsion, by combining with them the proper solvents and emulsifying agents, under proper conditions of temperature and agitation. The consistency of the liquid is preferably similar to that of heavy paint, so that it will form seals along the mouths of the recesses underlying the plaster keys.

Sodium silicate, because of its properties as an adhesive, fire and moisture resistant, is very desirable as a binder in the compound.

Metallic aluminum, because of its non-inflammability, heat and moisture resistance, is used as a filler to prevent porosity. By filling the pores of materials such as found in a plastered wall, it prevents breathing or loss of warm air and impregnation by moisture.

The production of a typical wax emulsion is accomplished substantially as follows, proportions being by weight:

	Parts
Waxes	6.8
Mineral spirits	30.
Fatty acids	2.8
Saponifying agent	1.
Water	59.4

To each pound, more or less, of the last-above compound, there is added substantially four pounds of sodium silicate solution and one per cent by weight of aluminum powder or flake.

The introduction of the mineral wool or other insulating material into the hollows of the wall is effected, of course, in a customary manner after the aforesaid spraying operation has been completed.

It will be understood, of course, that the in-

vention, as embodied in the method above described is not limited to the use of any specific type of moisture-proofing solution, nor to the simultaneous use of the compressed air and vacuum to effect cleansing of the surfaces intended to be sprayed with the moisture proofing compound.

I claim as my invention:

1. The herein-described method of moisture-proofing a lath-plaster wall surface along the face thereof constituting a surface of a wall hollow, which consists in first cutting an opening into the hollow, then inserting into the said hollow through said opening a means for and therewith effecting cleansing of the surface to be moisture-proofed and manipulating said means from the exterior of said hollow until said surface is cleansed, then removing said means and thereafter inserting into said hollow a means for and therewith effecting the spraying of a moisture-proofing substance upon said surface to be moisture-proofed and manipulating said last-named means from the exterior of the hollow until said surface is completely coated with the moisture-proofing material and then removing said last-named means, then filling said hollow with insulating material and then closing said opening.

2. The herein-described method of insulating the walls of a building which consists in first providing a temporary means of access to hollows in said walls, then introducing into said hollows through said means of access and operating from the exterior of said hollows means for removing dust and the like from wall surfaces of said hollows and simultaneously therewith effecting discharge of said dust and the like from said hollows, then similarly effecting the spraying of said cleansed surfaces with a moisture proofing material, then filling the hollows with insulating material through said means of access, and then closing the latter.

3. The herein-described method of insulating the walls of buildings which consists in first preparing the hollows of said walls to receive insulating material, such as mineral wool, which consists in first providing means of access to said hollows from the exterior of the building, then inserting through said means of access for manipulation within the hollows from the exterior thereof pneumatic means for and therewith freeing surfaces of the walls of the hollows of loose material and particles, such as dust, and pneumatically removing the latter from the hollows, thereafter and while said surfaces are free of said loose matter, withdrawing said pneumatic means from the hollow and inserting in place thereof a means manually manipulable and controllable from the exterior of the hollow for and therewith effecting the coating of said surfaces with a liquid coagulable coating for rendering said surfaces substantially impervious to the entrance of moisture into the hollows from the interior of the building, then withdrawing said last-named means from the hollows, then filling the latter with insulating material, such as mineral wool, and then closing said means of access to said hollows.

4. The herein-described method of insulating the walls of buildings which consists in first preparing the hollows of said walls to receive insulating material, such as mineral wool, which consists in first providing means of access to said hollows from the exterior of the building, then inserting through said means of access for ma-

nipulation within the hollows from the exterior thereof pneumatic means for freeing surfaces of the walls of the hollows of loose material and particles, such as dust, and therewith pneumatically removing the latter from the hollows, substantially simultaneously with the removal of said loose matter, thereafter and while said surfaces are free of said loose matter, withdrawing said pneumatic means from the hollow and inserting in place thereof a means manually manipulable and controllable from the exterior of the hollow for and therewith effecting the coating of said surfaces with a liquid coagulable coating for rendering said surfaces substantially impervious to the entrance of moisture into the hollows from the interior of the building, then withdrawing said last-named means from the hollows, then filling the latter with insulating material, such as mineral wool, and then closing said means of access to said hollows.

5. The herein-described method of insulating the walls of buildings, which includes a series of steps consisting in first providing means of access to hollows in said walls between studs thereof, thereafter inserting through said means of access for manipulation within said hollows from the exterior of said walls, equipment for and therewith by manipulation thereof, spraying selected surface portions of said hollows with

10 a liquid coagulable moisture proofing substance adapted to prevent intrusion of moisture into said hollows from the interior of the building, then removing said equipment from said hollows, then filling the latter with insulating material, such as mineral wool, and then closing said means of access.

15 6. The herein-described method of insulating the walls of buildings, which includes a series of steps consisting in first providing openings for access to the upper ends of hollows in said walls between studs thereof, providing flexible hose connected at one end with sources of supply of liquid coagulable moisture proofing substance and a source of supply of compressed air, respectively, and at the other end with a conventional means utilizing said liquid and air for spraying said liquid, thereafter inserting said means and part of the hose through said openings and manipulating the spraying means by means of said 20 hose, from the exterior of the building to cause said spraying means to coat selected surfaces of the hollows to prevent intrusion of moisture into the same from the exterior of the building, then withdrawing the hose and spraying means from said hollows, then filling the latter with insulating material, such as mineral wool, and then closing said openings.

25 EDWARD F. CUSICK.
